Paul E. Green, Inventor
By his Attorney A. J. O'Brien

UNITED STATES PATENT OFFICE.

PAUL E. GREEN, OF GEORGETOWN, COLORADO.

ADVERTISING-BOARD.

SPECIFICATION forming part of Letters Patent No. 484,194, dated October 11, 1892.

Application filed December 8, 1891. Serial No. 414,429. (No model.)

To all whom it may concern.

Be it known that I, PAUL E. GREEN, a citizen of the United States of America, residing at Georgetown, in the county of Clear Creek 5 and State of Colorado, have invented certain new and useful Improvements in Advertising-Boards; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to improvements in advertising-boards; and the object of the improvement is to provide a device of the class stated in which suitable type-blocks forming any desirable advertising matter may be set 20 up and locked at will, said blocks, however, being removable at pleasure for the purpose of changing the advertising matter of the board. Hence the invention relates to a special construction of type-blocks, as well as to 25 the board, case, or frame for supporting or holding the same, the improvement being of simple and economical construction, thoroughly practicable, reliable, durable, and efficient in use.

30 To these ends the invention consists of the features hereinafter described and claimed.

In the accompanying drawings is illustrated an embodiment of my improved device.

Figure 1 of the drawings is a top or plan 35 view of the improvement. Fig. 2 is an edge view of the device. Fig. 3 is a transverse section taken through the board from the top to the bottom. Fig. 4 is a detail view of one of the type blocks or sections of the board.

40 Fig. 5 illustrates the locking-rod.

As shown in the drawings, the framework of the device consists of a rectangular open case 5, centrally divided by a partition 6, forming a double receptacle for the type-blocks 7.

45 To one side of the device, which I will term the "top," are secured rings, by means of which the case may be suspended and the matter set upon both sides exhibited or exposed to view. The sides of the case consist of a double flange or 50 rim of any suitable depth, preferably equal to the thickness of the type blocks or sections employed in connection therewith. One side of

this flange—the top or bottom (as shown in the drawings the top)—is preferably provided with a fixed or stationary tongue 9, adapted 55 to engage or enter a correspondingly-shaped recess or groove 10, formed in the type-blocks. Hence the work of setting up advertising matter must be commenced at the side provided with the stationary tongues. The first 60 row of blocks having been placed in position, a locking-rod 12 is run through openings 13, formed in two opposite sides of the flange, said openings being so located that the rods when in position shall fit nicely in the recesses or grooves 10 of the sections 7. The rods and sections are of such relative construction that the grooves 10 of the blocks on one side shall receive one half of the locking-rod, the other half of the rod forming the 70 tongue to engage the recesses or grooves of the next set or row of blocks, and so on in succession from the top to the bottom of the board or until the required matter is set up, each successive rod inserted locking a row of 75 type blocks or sections in place. The blocks may be made of different sizes, as shown in Fig. 1. For instance, the apertures in the flanges for the locking-rods are formed close enough together to accommodate the small- 80 est-sized blocks which it is desired to use. The larger blocks will then be constructed of such size as to exactly occupy the space of two or more of the smaller blocks. Hence when the larger blocks are employed one or 85 more locking-rods will be omitted, depending on the size of the blocks employed. The larger blocks are of the same construction as the smaller in every respect except as to size and are retained or locked in position in the 90 same manner. The locking-rods have heads on one extremity and are provided at the opposite extremity with any suitable retaining means. As shown in the drawings, the rods are angular near the head to fit an opening 95 of corresponding shape in the flange, while the opposite extremity is threaded to receive a suitable nut. The object of the angular portion of the rod is to prevent the same from turning when screwing on the nut. The rods 100 may, however, be secured in position in any other suitable manner.

As shown in the drawings, the device is double, or composed of two sides substantially

alike. A single device or case having but one flange may of course be employed, if desired.

It will thus be seen that my improved device affords a handy, convenient, and attractive means for advertising any business of such a nature as to require a frequent change in the matter exhibited.

Having thus described my invention, what I claim is—

1. The combination, in a sectional advertising-board, of recessed or grooved type-blocks, a supporting-frame therefor, and locking-rods for holding the type-blocks in place in the frame, which is provided with apertures for the reception of these rods, which engage the recesses in the blocks, substantially as described.
2. In an advertising-board, the combination

of a double supporting-frame, two sets of rods therefor suitably connected with the frame, and recessed blocks which said rods engage, substantially as described.

3. In a sectional advertising-board, the combination of a supporting-frame provided on one side with a stationary tongue, type-blocks grooved to engage said tongue, locking-rods for the type-blocks, and apertures formed in the frame to receive said rods, substantially as described.

In testimony whereof I affix my signature in presence of two witnesses.

PAUL E. GREEN.
